UNITED STATES PATENT OFFICE.

HENRY J. GOFF, OF STOCKTON, CALIFORNIA, ASSIGNOR TO STOCKTON BOX COMPANY,
OF STOCKTON, CALIFORNIA, A CORPORATION.

METHOD OF AND APPARATUS FOR MAKING BOX LIDS.

Application filed October 18, 1926. Serial No. 142,202.

This invention relates to the lids or covers used for boxes in which fruits such as grapes are packed for shipment. Such lids are commonly made of a pair of transversely aligned boards with end cleats to hold the boards together. The boards and cleats are both quite thin and at present the cleats are usually secured to the boards by wire stitching, which requires the use of a complicated and expensive machine. Lids so constructed have the disadvantages of a lack of neatness of appearance, and the sharp ends of the wires frequently project from the surface of the wood and are apt to stick into and scratch the hands of those subsequently handling the lids and boxes. I make such lids by glueing the end cleats onto the boards, avoiding the use of wires, and so that the finished lid presents a neat and perfectly smooth appearance, and is more convenient to handle. In thus making the lids the boards must be laid side by side, the glue applied to one face of the cleats and the latter then applied to the boards, and clamping pressure must then be exerted against the boards and cleats to hold the parts in close relationship until the glue has thoroughly set.

The principal object of my invention therefore is to provide a method for accomplishing these operations in a quick, economical and commercially practicable manner, and an apparatus for enabling the method itself to be carried out. Apart from the improved appearance and form of the lid itself, the apparatus I use in connection with their manufacture enables a large number of lids to be put out with but very little initial expense for equipment as compared with the wire stitching machines, and without the need of skilled labor being employed. Also the capacity or output of any plant may be increased indefinitely with but a small additional outlay of capital, and with but a few additional operators.

These objects I accomplish by means of such structure and relative arrangement of parts as will fully appear by a perusal of the following specification and claims.

50 In the drawings similar characters of reference indicate corresponding parts in the several views:

Fig. 1 is a plan view of the permanent features of the apparatus used in connection 55 with my method.

Fig. 2 is a side elevation of the apparatus as a whole showing boxes in process of manufacture in accordance with my method.

Fig. 3 is a perspective view of a lid.

Fig. 4 is a side elevation of a lid guide 60 and clamp supporting unit of the apparatus showing the clamps in place in their initial position.

Fig. 5 is a side elevation of a stack of lids as mounted in the clamps and supported on 65 the setting runway.

Fig. 6 is a perspective elevation of a clamp.

Fig. 7 is a perspective view of a fixed board guide and clamp supporting member 70 as mounted on the table.

Fig. 8 is a sectional perspective of the glue vessel used in glueing the end cleats.

Referring now more particularly to the characters of reference on the drawings, the 75 main unit of the permanent installation of the apparatus comprises a table 1 of suitable height and length having two longitudinal supporting surfaces 2 and 3 preferably separated by a longitudinal partition 4. 80

Mounted on the table may be any desired number of units for assembling lids. Each unit comprises a pair of rigid upstanding transverse members 5, preferably heavy boards which are mounted on the surface 2 85 and are spaced longitudinally thereof. This spacing is sufficient to receive a lid board B lengthwise therebetween, while the width of the members 5 transversely of the table is sufficient to receive two such lid boards in 90 transversely aligned relationship. Disposed along the table at the front and back edges of the members 5 and extending therebetween are sills 6 which are recessed adjacent the inner faces of the member 5, as shown 95 at 7 in Fig. 7. Mounted on the members 5 at the top and against the outer faces thereof and extending beyond the front and back side edges are horizontal straps 8 which are bent at their outer ends toward the inner faces of the members 5 to form end flanges 9, which flanges are disposed parallel to the corresponding edges of said members and some distance outwardly thereof.

In connection with each pair of members 5 I use a pair of clamps. Each clamp comprises a rectangular rigid frame 10 having an internal width slightly greater than the members 5, and a height considerably 110

greater than said members. A clamping bar 11 is slidably mounted in the frame adjacent the top thereof for vertical movement, said bar being connected to the top member of the frame and adjustable up or down by means of a screw 12 threaded through said top member. The upper end of the screw is preferably squared so that a hand wheel as shown at 13 in Fig. 2, or 10 the chuck of a pneumatic tool, may be applied to the screw to turn the same.

Adapted to be mounted on the table surface 3 in transverse alignment with each lid assembling unit is a glue vessel. This vessel comprises an outer rectangular pan 14, to rest on the surface 3, and to be held in proper alignment relative to the assembling unit between transverse and longitudinally spaced guides 15. Arranged to move vertically in the pan 14 and to float on the glue 16 therein is a shallower pan 17. This pan has a pair of spaced and upwardly projecting flat topped ridges 18, which extend transversely and are spaced longitudinally relative to the table. The ridges are longitudinally slotted as at 19, the slots communicating with the glue under the pan. The length of the ridges is somewhat greater than that of the end cleats C of the lid and are practically as wide as said cleats. The table surface 2 between the lid assembling units is arranged to support a number of stacks of lids B; while the surface 3 between the different glue vessels is arranged to support a supply of the cleats C, as shown in Fig. 2.

In operation a pair of clamps is mounted in connection with each pair of members 5, before the lid assembling operations are begun, by sliding each clamp in turn transversely of the table so that the lower end of the clamp frame rests in a pair of recesses 7. The clamp frame is then supported by the sills 6. The partition 4 at the back prevents the clamp from going too far transversely of the table and holds it so that if it is then tilted toward the adjacent member 5, the sides of the clamp frame will clear the edges of said member, 45 enabling the sides of said frame to rest against the metal straps 8. The clamping bar 11 is of course retracted so that it clears the top of the member 5. The straps 8 being on the outer faces of the said members and the recesses 7 being at the inner faces thereof, the clamp will lie at an angle such that it is self-supporting, as clearly shown in Fig. 4. Both clamps being in position one operator then takes a stand in front of the assembling unit, and another one on the opposite side of the table, in front of the corresponding glue table. The first operator takes two boards B from the adjacent stack on the table and places them 65 between the members 5 and the clamp

frames so that they rest on the bottom of said frames, which are immediately adjacent said members. The second operator in the meantime takes two cleats in his hands, rests them on the ridges 18 of the glue vessel so that they will receive some glue oozing through the slots 19, and places said cleats, glued faces down, on top of the boards B at the ends thereof, or against the members 5, which form guides for the placing of the cleats. The first operator then places another pair of boards B on top of the cleats thus placed, while the second operator is preparing another pair of end cleats to be placed on said other pair of boards. These operations are continued until the number of lids thus assembled reaches adjacent the top of the members 5. The clamps are then swung toward each other from their upper ends until they are vertical or parallel to each other, in which position the clamping bars 11 are vertically aligned with the vertical rows of the end cleats. The bars 11 are then advanced until the necessary pressure is exerted strongly on all the lids. This pressure, as will be evident, only comes where it is needed i. e. between the cleats and the adjacent surfaces of the boards. The separated boards between the cleats are therefore not subjected to any pressure which would tend to warp or distort them.

The clamps and the lids secured therein are then removed from the assembling table as a unit and placed on a gently inclined runway 20. This runway is formed with longitudinal rails 21, having raised ridges 22 extending lengthwise thereof, which are spaced apart the same as the spacing between the clamp members when the latter are secured to the lids. The clamp frames are made with their bottoms longitudinally grooved, so as to fit over the ridges, which therefore guide the frames in their movement lengthwise of the runway. The runway extends in any desired direction from the table, depending on the space available or the general lay out of the plant, and is of such a length as to insure that by the time a lid and clamp unit has been pushed from the top to the bottom of the runway by successive units, the glue of the lids of the first unit will be sufficiently hardened to enable the clamps to be removed. This done and the lids stored or carried away, the clamps are placed on a return chute 23 which leads from adjacent the lower end of the runway 20 to a point adjacent the table 1. This enables the clamps to be then picked up when needed and again mounted in connection with the assembling units without lost time or motion on the part of the operators.

As many assembling units as it may be necessary to give the desired capacity may

be mounted either on a single table or on separated tables, and a number of runways arranged in transverse relationship to deliver to a common point may also be used.

5 From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended 15 claims.

Having thus described my invention what I claim as new and useful and desire to secure by Letters Patent is:

1. A method of making box lids formed 20 of transversely alined boards and end cleats glued across the board, as the lids are made, consisting in assembling a plurality of the component parts of the lids in proper and superimposed order to form a stack, and 25 then applying a clamping pressure to the stack as a unit in the planes of the end cleats.

2. A method of making box lids formed 30 of transversely alined boards and end cleats glued across the board, as the lids are made, consisting in assembling a plurality of the component parts of the lids in proper and superimposed order to form a stack, supporting the parts in opposed clamp frames 35 as they are assembled, said frames being disposed at the ends of the lids, and then applying a vertical clamping pressure onto all the end cleats simultaneously by means of said clamp frames.

40 3. A method of making box lids formed of transversely alined boards and end cleats glued across the board, as the lids are made, consisting in assembling a plurality of the component parts of the lids in proper and superimposed order to form a stack, supporting the parts in opposed clamp frames 45 as they are assembled, said frames being disposed at the ends of the lids, then applying a vertical clamping pressure onto all 50 the end cleats simultaneously by means of said clamp frame, and finally permitting the clamps and lids to remain undisturbed for a predetermined time to permit the glue to set before removing the clamps.

55 4. A method of making box lids formed of transversely alined boards and end cleats glued across the board, as the lids are made, consisting in assembling a plurality of the component parts of the lids in proper and superimposed order to form a stack, supporting the parts in opposed clamp frames 60 as they are assembled, providing for the removable support of the frames at the ends of the lids and the locating of the lid parts 65 relative to the frames, then applying clamp-

ing pressure to all the end cleats from the top, by means of the clamping elements provided with the frames, then removing the frames and lids clamped therein from the supporting means, and allowing the unit 70 to remain undisturbed until the glue has set.

5. A method of making box lids formed 75 of transversely alined boards and end cleats glued across the boards, as the lids are made, consisting in assembling a plurality of the component parts of the lids in proper and superimposed order to form a stack, then applying a clamping pressure to the stack as a unit in the planes of the end cleats, and maintaining the clamping pressure un- 80 disturbed for a predetermined time.

6. A method of making box lids formed 85 of transversely alined boards and end cleats glued across the boards, as the lids are made, consisting in providing fixed locating means for the parts of the lids, placing the boards in proper relationship with the locating means, from one side thereof, placing the cleats on the boards from the other side of the locating means, applying an adhesive 90 to one face of the cleats before they are thus applied, assembling a stack of the lids by thus placing the boards and cleats alternately, and finally applying a clamping pressure to the stack in the vertical planes of the 95 end cleats.

7. Apparatus for making box lids which consist of transversely alined boards with 100 end cleats glued across the boards, including fixed upstanding elements spaced to receive a board therebetween and having a width approximating that of a lid, rectangular frames wider than said elements, clamping bars mounted in said frames adjacent the top and parallel to the bottom 105 thereof, and means provided in connection with said elements for removably supporting the frames so that their bottoms lie just inwardly of the elements and their sides lie at an upwardly diverging slope 110 relative to each other.

8. Apparatus for making box lids which consist of transversely alined boards with 115 end cleats glued across the boards, including fixed upstanding elements spaced to receive a board therebetween and having a width approximating that of a lid, rectangular frames wider than said elements, clamping bars mounted in said frames adjacent the top and parallel to the bottom thereof, horizontal members at the front and back of said elements at the base thereof and extending therebetween, said members having recesses in their upper faces disposed to support and locate the bottoms of the frames adjacent 120 and inwardly of the elements, and supporting means for the sides of the frames toward their upper ends, projecting beyond the side edges of the element from the opposed 125 faces thereof.

9. Apparatus for making box lids which consist of transversely alined boards with end cleats glued across the boards, including fixed upstanding elements spaced to receive a board therebetween and having a width approximating that of a lid, rectangular frames wider than said elements, clamping bars mounted in said frames adjacent the top and parallel to the bottom thereof, horizontal members at the front and back of said elements at the base thereof and extending therebetween, said members having recesses in their upper faces disposed to support and locate the bottoms of the frames adjacent and inwardly of the elements, supporting means for the sides of the frames toward their upper ends, projecting beyond the side edges of the element from the opposed faces thereof, a vessel to contain a liquid adhesive for the end cleats, and means for supporting the vessel in direct association with and between said elements in a plane to one side thereof.

10. Apparatus for making box lids which consist of transversely alined boards with end cleats glued across the boards, including fixed upstanding elements spaced to receive a board therebetween and having a width approximating that of a lid, rectangular frames wider than said elements, clamping bars mounted in said frames adjacent the top and parallel to the bottom thereof, means provided in connection with said elements for removably supporting the frames so that their bottoms lie just inwardly of the elements and have their sides lie at an upwardly diverging slope relative to each other, and transversely separated surfaces mounted as a unit with the elements for supporting supplies of the boards and cleats in separated relationship.

11. Apparatus for making box lids which consist of transversely alined boards with end cleats glued across the boards, including fixed upstanding elements spaced to receive a board therebetween and having a width approximating that of a lid, rectangular frames wider than said elements, clamping bars mounted in said frames adjacent the top and parallel to the bottom thereof, means provided in connection with said elements for removably supporting the frames so that their bottoms lie just inwardly of the elements and have their sides lie at an upwardly diverging slope relative to each other, transversely separated surfaces mounted as a unit with the elements for supporting supplies of the boards and cleats in separated relationship, a vessel to contain a liquid adhesive for the end cleats, and means on the cleat supporting surface for locating the vessel in transverse central alinement with the elements and to one side of the same.

12. Apparatus for making box lids which consist of transversely alined boards with

end cleats glued across the boards, including fixed upstanding elements spaced to receive a board therebetween and having a width approximating that of a lid, rectangular frames wider than said elements, clamping bars mounted in said frames adjacent the top and parallel to the bottom thereof, means provided in connection with said elements for removably supporting the frames so that their bottoms lie just inwardly of the elements and their sides lie at an upwardly diverging slope relative to each other, board supporting surfaces longitudinally alined with the elements beyond the same, and a cleat supporting surface parallel to said first named surfaces and disposed to one side of the elements.

13. Apparatus for making box lids which consist of transversely alined boards with end cleats glued across the boards, rectangular clamp frames to support the lid-boards at their ends, clamping bars in the frames adjacent the upper ends thereof and arranged for vertical movement, and means for removably supporting the frames while a stack of lids is being assembled therein, the clamping bars being advanced against the end cleats when the stack is completed.

14. Apparatus for making box lids which consist of transversely alined boards with end cleats glued across the boards, rectangular clamp frames to support the lid-boards at their ends, clamping bars in the frames adjacent the upper ends thereof and arranged for vertical movement, means for removably supporting the frames while a stack of lids is being assembled therein, the clamping bars being advanced against the end cleats when the stack is completed, and a runway on which the clamped lids, with the frames as a unit therewith, are then placed.

15. Apparatus for making box lids which consist of transversely alined boards with end cleats glued across the boards, rectangular clamp frames to support the lid-boards at their ends, clamping bars in the frames adjacent the upper ends thereof and arranged for vertical movement, means for removably supporting the frames while a stack of lids is being assembled therein, the clamping bars being advanced against the end cleats when the stack is completed, a runway on which the clamped lids, with the frames as a unit therewith, are then placed, and means between the runway and frames for guiding the unit on the runway.

16. Apparatus for making box lids which consist of transversely alined boards with end cleats glued across the boards, rectangular clamp frames to support the lid-boards at their ends, clamping bars in the frames adjacent the upper ends thereof and arranged for vertical movement, means for removably supporting the frames while a stack of lids is being assembled therein, the clamp-

ing bars being advanced against the end cleats when the stack is completed, a runway on which the clamped lids, with the frames as a unit therewith, are then placed, the bottoms of the frames being longitudinally grooved on the outside, and longitudinal ridges on the runway to fit the grooves of the frames and spaced apart a distance equal to the spacing of the frames when the latter are clamped onto the lids.

17. Apparatus for making box lids which consist of transversely aligned boards with end cleats glued across the boards, rectangular clamp frames to support the lid-boards at their ends, clamping bars in the frames adjacent the upper ends thereof and arranged for vertical movement, means for removably supporting the frames while a stack of lids is being assembled therein, the

clamping bars being advanced against the end cleats when the stack is completed, a runway on which the clamped lids, with the frames as a unit therewith, are then placed, and a return chute for the detached clamps leading from adjacent one end of the runway to adjacent the clamp supporting means. 25

18. A means for applying an adhesive to the end cleats of a box lid comprising an outer pan, to contain the adhesive, an inner pan to float on the adhesive, and flat-topped ridges approximating in size the face area 30 of a cleat, projecting upwardly from the bottom of the inner pan in spaced relation to each other and to the sides of said pan; said ridges having longitudinal slots therethrough communicating with the adhesive. 35

In testimony whereof I affix my signature.

HENRY J. GOFF.
